CLEANING DEVICE

Dorothy F. Rodgers, New York, N. Y.

Application December 8, 1943, Serial No. 513,438

5 Claims. (CL 15—210)

1

The present invention relates to cleaning swabs and the like, and particularly to swabs for use in cleaning toilet bowls and the like.

Conventional devices commonly employed for the cleaning of toilet bowls and the like are bound up with numerous disadvantages. Among these may be mentioned their generally relatively insanitary character after use, which makes it extremely desirable to dispose of them directly after such use.

A desideratum in devices of this character is, manifestly, maximum ease of disposability with minimum impairment of cleaning capacity.

A primary object of the present invention is the development, in a device of the aforementioned character, of a relationship of parts which makes it possible to a very high degree to realize the afore-indicated desideratum.

In a presently-preferred embodiment of the invention, the device consists essentially of a cleaning pad and a quick-associable and -dissociable handle therefor. An important feature of the device is that dissociation of the pad, in its insanitary state following use thereof for its intended purpose, may be easily effected without the necessity of handling or touching the pad.

A further important feature of the device is the structure of the pad whereby sufficient rigidity is imparted thereto to enable the cleaning operation to be effected, whereupon the action of the water in the bowl reduces the pad to a state of deterioration such that, after dissociation from the handle, it may be flushed down the toilet bowl with no danger of clogging the drain.

Still another important feature of the invention is the provision, essentially wholly interiorly of the pad, of a hollow receptacle for the reception of handle means by a snap button action. The receptacle, according to the invention, is constructed from non-metallic materials and combines the important characteristics of sufficient strength and rigidity to effect its intended function and of ready disposability.

Other objects and advantages of the invention will be evident from the following detailed description thereof with reference to the accompanying drawing, wherein:

Fig. 1 is a sectional view of the handle and pad elements of the cleaning device of the invention, the parts being dissociated for clearness of view;

Fig. 2 is an end view of the ball-shaped end of the handle element;

Fig. 3 is a plan view of the reinforcing disk;

Fig. 4 is a fragmentary sectional detail, show-

2

ing the female receptacle provided on the pad;

Fig. 5 is a plan view, illustrating an intermediate phase in the production of the said receptacle;

Fig. 6 is a sectional view through a modified embodiment of pad; and

Fig. 7 is a detail view, showing a method of disassembling the device.

Referring first to Fig. 1 of the drawing and to 10 the embodiment of the invention disclosed therein, it will be seen that the pad element according to this invention may be comprised essentially of a cup member 10 and a cover member 11 associative therewith, filler material 12 15 filling the hollow pad interior defined by members 10 and 11, handle-securing means 15 (hereinafter described in greater detail), and suitable means 13 for stiffening the cover member 11 and for associating said handle-securing means there- 20 with.

Cup 10 and cover 11 may conveniently be made of a sheet or sheets of disposable paper, tissue, pulp or other cellulosic material, preferably impregnated with a solution of water-soluble material, such as water-soluble carbohydrate, for example, starch or glucose, gelatine, glue or vegetable gum or the like or an admixture thereof. The sheets obtained, after drying the solution, possess sufficient plasticity to enable them to be 25 shaped, e. g., cupped, in a suitable die, and sufficient rigidity to enable the shaped product to retain its shape.

The paper or cellulosic material must itself be of a type which has a relatively low resistance 35 to water, i. e., is essentially disintegrable upon sufficiently prolonged contact with water. It must, however, be sufficiently stable to enable the aforementioned impregnation to be carried out. Material of this character is readily available; use may be made of toilet paper, paper toweling, etc., for example, that of the so-called "Scot Tissue" type, or else the cellulosic material of which the well-known disposable sanitary napkins are made may be employed.

45 The disintegrability or "water-solubility" of the cellulosic material, together with the water-solubility of the impregnating material, render the cup 10 and cover 11 readily disposable, for example, by flushing down the toilet bowl, after 50 essential disintegration thereof. The impregnating material tends to retard this disintegration for a sufficient time to enable the cleaning operation to be carried out.

The gelatine, starch or other impregnating material, and particularly that used for impreg-

nating cup member 10, may be admixed with soap powder, "Bon Ami" or any other suitable and convenient cleaning material capable of imparting enhanced cleaning characteristics to the impregnated material, thereby better adapting the pad to its intended purpose.

The filler material 12 may conveniently be of the same material as the cup and cover members, except that it need not be impregnated nor need it have sheet characteristics. It is sufficient for this purpose to employ any readily disposable material, such as paper clippings or scrap cellulosic material or the like.

In order to assure maintenance of the pad structure until the cleaning operation is completed, mechanical means in the form of a reinforcing disk 13 may preferably be provided interiorly of and contiguous to the cover 11. This disk, which may be circular or of any other suitable configuration, depending upon the pad configuration, may also be made of the aforesaid paper or cellulosic material and is preferably impregnated with ordinary cabinet-maker's or carpenter's glue which, after impregnation, is allowed to dry and harden. Disk 13, when positioned within the pad as shown in Fig. 1, will enable the latter to retain its shape and will thereby commensurately facilitate the cleaning operation. This is due to the fact that the disk 13 will disintegrate or "dissolve" more slowly than the hereinbefore described elements of the device. Disk 13 is provided with a central opening 14 to permit of the passage of the female receptacle. This receptacle constitutes the means whereby the pad may be associated with an operating holder or handle member 16 in the manner hereinafter described.

Handle member 16 may be constituted of any suitable or desirable material of sufficient strength and resistance to water. It may, for example, conveniently comprise an enameled wooden rod provided at one end with a hook or the like and being counterbored at the other end for the secure reception of the shank 18 of the ball-shaped head 19. The latter is preferably slotted as shown in Figs. 1 and 2 so as to be yieldingly associative with the correspondingly configured receptacle 15 by a snap button effect. Parts 18, 19 may be made of any suitable water-resistant material, e. g., brass or the like. The fit between shank 18 and the handle 16 is, of course, sufficiently tight to assure against undesired separation of these parts. Handle 16 may also be made of suitable water-resistant synthetic resinous material, such, for example, as molded melamine-formaldehyde condensation product.

Female receptacle 15 may conveniently be built up on a basis of gauze impregnated with paraffin wax or with a suitable gum or the like. A presently preferred method of forming the receptacle involves superposing a plurality of strips of impregnated gauze 20 in the criss-cross fashion shown in Fig. 5 whereby a central laminated portion of sufficient thickness and strength to form the receptacle proper is produced. The associated criss-crossed strips are then pressed into a mold and, with the aid of a warm forming tool, are caused to conform to the inner configuration of the mold which is of a character to impart the illustrated essentially hollow spherical configuration to the resultant molded receptacle 15. Use is preferably made of a split mold in order to facilitate removal in intact form of the molded receptacle. The size of the receptacle is, of course,

adapted to that of the head 19. The shaped receptacle 15 is then dipped in glue, preferably ordinary carpenter's glue, which is allowed to dry and harden.

Assembly of the pad may conveniently be effected as follows: Receptacle 15 is inserted in opening 14 of disk 13 to which the free ends of strips 20 are then attached by means of glue. Disk 13 and associated receptacle 15 are then inserted in cover member 11 and glued into place therein. The mouth of the receptacle is, of course, aligned with the corresponding opening 21 in the cover. Cup member 10 is then filled with cellulosic filler 12 and the cover member 11 is then telescoped thereover into place. A peripheral strip of impregnated paper 17 may be glued into place to seal the joint between cover and cup.

Fig. 6 shows a modified embodiment of pad structure according to which the cup member 10' consists of gauze-covered cellulosic material, such as is commonly used in sanitary pads for feminine hygienic purposes. Cover member 11' is disk-shaped in this embodiment, and the edges of the member 10' are glued or otherwise secured therebetween and the reinforced-receptacle assembly 13, 15. This embodiment may also conveniently comprise filler material 12, as hereinbefore described.

It will be manifest from the above that the described device constitutes a realization of the objects of the invention. The pads are readily disposed of and, due to the essential disintegrability thereof, there is no danger of clogging of plumbing appliances. The pads are conveniently stored in a suitable cardboard container and, due to their biscuit-like configuration, with a minimum space requirement.

The handle 16 is easily associated with the pad by movement relative to the latter in the direction of the arrow shown in Fig. 1. After use, the soiled pad may be dissociated from the handle, without having to be touched, in the manner illustrated by way of example in Fig. 7, where the pad is placed against the edge of the bowl 22 and drops into the latter, upon pulling of the handle 16 in the direction of the arrow, to be flushed away.

Solutions which may be employed for impregnating the cellulosic material employed for the purpose of the present invention are known and do not, per se, constitute a part of the invention. An illustrative solution which may be employed may comprise 1 part of glue, 2 parts of glucose and 3 parts of water. An aqueous solution of glue alone or of soluble starch will also give satisfactory results.

The above detailed description of the invention is primarily illustrative, and not at all limitative, in character, and various modifications may be effected within the scope of the following claims without departing from the spirit of the invention. Thus, the parts 10, 11, 11' and 13 may, for example, be laminated up to any desired thickness with the aid, for example, of water-soluble glue.

Having disclosed the invention, what is claimed is:

1. A cleaning swab pad of water-disintegrable cellulosic material comprising a reinforced portion of retarded water-disintegrability, and socket means in said portion for the reception of a ball-shaped handle end, whereby said swab pad is readily removable from said handle while in operative position and without handling thereof.

2. A swab pad according to claim 1, said socket means consisting essentially of a molded receptacle of glue-impregnated gauze.

3. A cleaning swab for toilet bowls and the like, which comprises a cleaning pad of essentially water-disintegrable material, whereby after use the pad is easily disposable in the toilet bowl, a handle therefor, said handle having connecting means located at one end thereof, connecting means located within the body of said pad and frictionally engageable with the connecting means of said handle whereby to interconnect said handle and pad, the connecting means located within the body of said pad including a portion of retarded water-disintegrability whereby when the handle and pad are interconnected there is initially a connection therebetween which is of sufficient strength to hold the parts together in position for a cleaning operation, the connecting means of said handle and pad being associable and dissociable essentially longitudinally of the handle, and the disintegration of said portion of retarded water-disintegrability during the said cleaning operation facilitating the aforesaid dissociation without the necessity of handling the pad.

4. A cleaning swab for toilet bowls and the

like, which comprises a cleaning pad of essentially water-disintegrable material, whereby after use the pad is easily disposable in the toilet bowl, a handle therefor, connecting means on said handle, said pad comprising a hollow cup member and a reinforced cover therefor, filler material in the space defined by said cup member and cover, and means in said cover for the quick association of said pad with and quick dissociation thereof from said connecting means on said handle, said cup member being made of paper impregnated with a water-soluble stiffener.

5. A cleaning swab for toilet bowls and the like, which comprises a cleaning pad of essentially water-disintegrable material, whereby after use the pad is easily disposable in the toilet bowl, a handle therefor, connecting means on said handle, said pad comprising a hollow body member and a reinforced cover associated therewith, filler material in the space defined between said body member and cover, and receptacle means in said cover for the rapid association and dissociation of said pad with said connecting means on said handle, said body member being made of exteriorly gauze-covered cellulosic wadding.
